[57] CLAIM

The ornamental design for a combined chair and hydrotherapy unit for legs, substantially as shown and described.

DESCRIPTION

FIG. 1 is a perspective view taken from the left side of a combined chair and hydrotherapy unit for legs showing my new design;

FIG. 2 is a perspective view taken from the right side thereof;

FIG. 3 is a perspective view taken from the front thereof;

FIG. 4 is a perspective view taken from the rear thereof;

FIG. 5 is a perspective view taken from the rear and left side thereof;

FIG. 6 is a perspective view taken from the top and rear thereof, showing the cover in an open position; and

FIG. 7 is a perspective view taken from the front and left side thereof.

FIG. 1

FIG. 2

FIG. 3

FIG. 4

FIG. 5

FIG. 6

FIG. 7
